UNITED STATES PATENT OFFICE.

MYRON J. SOUTHWICK, OF COLLEGE HILL, PENNSYLVANIA, ASSIGNOR, BY MESNE ASSIGNMENTS, TO ROSSMAN CORPORATION, OF BEAVER FALLS, PENNSYLVANIA, A CORPORATION OF DELAWARE.

TILE-FETTLING MACHINE.

Application filed September 22, 1926. Serial No. 137,082.

This invention relates to tile fettling machines, more particularly to a machine for smoothing or trimming the edges of tile after leaving the tile press in which they are formed and before they are fired.

It is among the objects of this invention to provide a tile fettling machine of simple and durable mechanical construction, and in which all of the movable elements are actuated from a common driving source.

Another object of this invention is to provide a tile fettling machine which shall be adapted to fettle or smooth clay tile in relatively large quantities, the machine being adapted to receive all of the tile from a multiple tile-forming press and continuously convey the tile away from the press through a number of fettling members and cleaning brushes for smoothing the imperfectly formed edges and for chamfering the same if desired.

Tile fettling machines have been heretofore proposed which function to trim the edges of tile by passing the tile on a movable support through the fettling members to bring the latter to act upon opposite edges thereof, and to subsequently turn the tile by suitable means to present the untrimmed edges of the tile to additional fettling members. The prior art devices are objectionable mainly on account of their limited capacity for handling the tile. This has been done by providing an obstruction in the path of the tile which was of such form as to cause the tile to pivot or turn on its support to bring the untrimmed edges in alignment with the fettling members, the turning means being capable of handling but a single tile at a time.

In accordance with the present invention means are provided for turning a plurality of tile passing through the fettling devices simultaneously, whereby the capacity of the machine is materially increased. In addition means are provided for guiding the tile as they pass from the tile-forming press to the fettling members in such a manner that after they have been acted upon to trim some of their edges they are conducted to the turning mechanism which rearranges the tile on their movable support to bring them in proper working alignment with subsequent or additional fettling members.

Another feature of the present invention

is the provision of dusting or smoothing 55 rolls or brushes which act upon the tile after they have been subjected to the fettling operation to remove any unevenness or loose particles adhering thereto prior to subjecting the tile to a coating operation for producing a glaze or finish thereon.

In the accompanying drawings constituting a part hereof and in which like reference characters designate like parts, Fig. 1 is a top plan view of a fettling machine embodying the principles of this invention; Fig. 2 is a side elevational view thereof partially in section; Fig. 3 is a vertical sectional view partially in elevation of a novel form 65 of fettling member, and Fig. 4 is an elevational view of a portion of the fettling device illustrating a tile being acted upon by a pair of fettling members.

Referring to Figs. 1 and 2 of the drawings, the structure therein illustrated comprises a frame or base consisting of a pair of side frames 1 supported on a standard 2 formed of pipes or other structural members suitably joined or secured and reinforced to provide adequate strength to the machine 80 frame. Upon the ends of the side frames 1 and at the intermediate portion thereof a plurality of rollers or spindles 3 and 4 are rotatably journaled, the spindles 3 carrying an endless conveyor belt 5 and the spindles 85 4 a similar belt 6, which, respectively, pass around driving drums 7 and 8 actuated by a common drive belt 9 passing around a sheave or pulley 10 of a countershaft 11 which is actuated by a drive motor 12. Suitable slack-adjustment or tension devices 13 are provided for the belt 6 to take up the slack in the belt and to keep it taut at the upper part of the machine frame portion between the rollers 3. A pair of revolving brushes 14 95 and 15 are mounted on the frames 1 and connected to sheaves or pulleys 16 carried by the countershaft 11 by belts 17 and 18.

A plurality of fettling devices such as is shown in Fig. 3 are mounted on the top portion of the machine above the moving conveyor belt 5 by means of angle brackets 20 which extend across the side frames 1 transversely of the path of movement of the belt 5. The fettlers consist of discs 21 which are secured by a screw 22 and collar 23 to a yieldable supporting strap 24 which is clamped to an adjustable block 25 mounted

in a support 26 by means of a screw threaded shank 27 which is vertically adjustable in its support. The coil spring 28 is interposed between the support 26 and the block 25 to yieldingly restrain the fettling member against vertical movement. The fettlers 10 may also be angularly adjustable by moving the same in its dove-tailed slot 29 and securing it in its adjusted position by the set screw 30.

The purpose of making the fettling member of disc shape is to permit adjustment of the fettling edge which in the disc member comprises loosening the screw 22 and 15 rotating the disc 21 a fraction of a turn until a clean and neat cutting or trimming edge is presented to the tile with which it comes into engagement.

As shown in Fig. 1 a plurality of guides 20 32 are secured by angle bars 33 in parallel relation to constitute guideways for receiving individual tile as it enters upon the conveyor belt 5. The guides are correlated with the fettling device 21 in such a manner that 25 the tile passing therethrough contacts with the fettlers in the region where they are to be trimmed which is usually the edges, which, in most instances, are chamfered or beveled as they pass through the fettlers.

30 After the tile has passed through the guides and the first group of fettlers 21 they pass along the conveyor belt 5 in a row extending across the path of movement of the belt until some of them engage a baffle member 35 and some a baffle member 36, which are pivoted to a cross brace 37 and one of the angle bars 20 respectively, as shown and are adapted to swing through arcs limited by the stops 35^a and 36^a respectively. The 35 baffle members are of such width as to engage a plurality of tiles simultaneously and since the adherence between the tile and their movable support 5 maintains contact of the tile with the baffle member they will be simultaneously turned through an arc as illustrated by the dotted line to rearrange their 40 position in a manner that will bring the untrimmed edges, that is, the edges that were not acted upon by the first fettling device 45 in alignment with the fettling members in the intermediate portion of the machine. After the tile have been rearranged or turned as shown in the illustration, they are conveyed through the additional fettling device 50 which smooths or trims their edges. The tile then passes underneath the brush 14 which removes the dust or fine particles from the surface of the tile and subsequently passes over the brush 15 which cleans the 55 underside of the tile.

60 When the tile has passed out of contact with the baffle arms 35 the latter spring back to their normal position which is transversely of the path of movement of the conveyor belt 5 until they become again engaged by

tile moving into contact therewith. For the purpose of maintaining the baffle members in their normal position a yielding restraining means such as a rubber strap or spring may be applied in the region of its pivotal joint.

65 It is evident from the foregoing description of the invention that tile fettling machines made in accordance therewith provide simple and efficient means for fettling all of the edges of a plurality of tiles simultaneously by passing them in rows through suitable guides underneath and in engagement with fettling members, and for automatically turning the tile after they are acted 70 upon by one group of fettling devices to present the untrimmed edges to an additional group of fettling members to finish the tile.

75 It is further obvious that tile fettling machines of this kind are especially adapted for fettling tile received from multiple tile forming presses having a relatively large quantity production.

80 Although one of the embodiments of the invention has been herein illustrated and described it will be obvious to those skilled in the art that various modifications may be made in the details of construction and in the arrangement of the several cooperating parts without departing from the principles 85 herein set forth.

90 I claim:

1. In a tile fettling machine the combination with a movable support for conveying tile before it is fired, of a plurality of fettling devices for acting upon opposite edges of the tile passing therebetween, means for turning a row of tile simultaneously to dispose their fettled edges transversely to the path of movement of their support, and additional fettling members adapted to act upon the untrimmed edges of the tile.

100 2. In a tile fettling machine the combination with a movable support for conveying tile before it is fired, of a plurality of fettling devices adapted to simultaneously act upon opposite edges of a plurality of tile disposed in a row transversely to the path of movement of said support, means for turning a plurality of tile simultaneously, and additional fettling members adapted to act 105 upon the untrimmed edges of the tile after it is turned.

110 3. In a tile fettling machine, the combination with a movable support for conveying tile before it is fired, of a plurality of fettling devices adapted to simultaneously act upon opposite edges of a plurality of tile, means for simultaneously turning or rearranging all of the tile on said support 115 after it has passed said fettling devices, and additional fettling devices for acting upon the untrimmed edges of said tile after it is turned.

120 4. In a tile fettling machine, the combina- 130

tion with a movable support for conveying tile before it is fired, of guides for distributing the tile in a row transversely of the path of movement of said support, fettling devices in cooperative alignment with said guides to act upon opposite edges of the tile, baffles mounted for pivotal movement in the path of movement of said tile and adapted to engage the same to arrange them in 10 rows at an angle to their original disposition, and additional fettling devices for acting upon the untrimmed edges of said tile.

5. In a tile fettling machine, the combination with a movable support for conveying 15 tile before it is fired, of guides and baffles for arranging and turning the tile on said support, and groups of fettling devices for acting upon the edges of said tile, said fettling devices comprising angularly adjustable cutting discs.

6. In a tile fettling machine, the combination with a movable support for conveying tile before it is fired, of guides and baffles for arranging and turning the tile on said

support, and groups of fettling devices for 25 acting upon the edges of said tile, said fettling devices comprising cutting discs adapted for adjustment angularly and vertically relative to said support.

7. In a tile fettling machine, the combination with a movable support for conveying tile before it is fired, of guides and baffles for arranging and turning the tile on said support, and groups of fettling devices for 30 acting upon the edges of said tile, said fettling devices comprising cutting discs rotatably adjustable to present new cutting edges to the tile.

8. In a tile fettling machine, the combination with a movable support for conveying 35 tile before it is fired, of guides and baffles for arranging and turning the tile on said support, fettling devices for acting upon the edges of the tile, and brushes for dusting the top and bottom faces of the tile after 40 leaving the fettling devices.

In testimony whereof, I sign my name.
MYRON J. SOUTHWICK.
